COMBINED DRIER AND ROOM
DEHUMIDIFIER

Robert R. Candor, Dayton, Ohio, assignor to
General Motors Corporation, Dayton, Ohio, a
corporation of Delaware

Application November 6, 1951, Serial No. 255,120

9 Claims. (Cl. 34—44)

1

This invention relates to domestic appliances and more particularly to a combined clothes dryer and room air dehumidifier.

Home laundry equipment usually is placed in the basement or in a small utility room. Previous clothes dryers of such equipment tend to discharge large quantities of water vapor into such basement or small utility room. This produces or aggravates high relative humidities in these places, causing undesirable rusting or 10 molding therein.

According to this invention, an apparatus is provided which is capable of drying clothes without producing harmful relative humidities during the drying operation in the space in which the apparatus is located, and which is capable of reducing undesirably high relative humidities which ordinarily are prevalent in such spaces during the time that such apparatus is not drying clothes.

The basement, utility room or similar place in which a clothes dryer is to be placed will be referred to hereafter as a "room," for convenience and brevity.

An object of this invention is to provide an apparatus having a room dehumidifier of normal capacity which is utilized to dehumidify room air and to store refrigerating capacity while the apparatus is not being used as a clothes dryer, and which utilizes the stored refrigerating capacity to condense the vapor driven off the clothes during a drying operation. This avoids the necessity of providing an excessively large refrigerating apparatus which otherwise would be necessary to condense the vapor in the short time during which clothes are being dried.

Another object of this invention is to provide a combined clothes dryer and room air dehumidifier of such a character that it dehumidifies the room air and stores up refrigeration capacity while the clothes dryer is inactive or is not drying clothes, and utilizes the stored up refrigerating capacity for condensing vapor from the clothes dryer while the clothes dryer is drying clothes.

Further objects of my invention will be apparent from the following description, reference being had to the accompanying drawings wherein preferred forms of the invention are clearly shown.

In the drawings:

Figure 1 is a diagrammatic view generally in vertical cross-section of a combined clothes dryer and room air dehumidifier embodying features of my invention; and

Figure 2 is a wiring diagram applicable to the apparatus shown in Figure 1.

2

A combined clothes dryer and room air dehumidifier, according to my invention, includes a clothes dryer cabinet 9 having a clothes drying chamber 10 and a vapor condenser 11 therein. The room air dehumidifier includes duct means 12 forming an air passageway through which room air is circulated through cabinet 9. A refrigerating system within cabinet 9 includes a refrigerant condensing portion (such as a refrigerant condenser 13 associated with a refrigerant motor-compressor 14) and a refrigerant evaporating portion (including one or more evaporators 15 and 16). The vapor condenser 11 is in the form of a closed insulated tank 18 having vapor condensing passages extending therethrough and contains a holdover medium 17. The medium 17 is provided for storing up refrigerating capacity during the period of time when the clothes dryer is inactive or is not drying clothes. Means for cooling the holdover 17 by the refrigerant evaporating portion of the refrigerating system while the clothes dryer is not drying clothes is provided. This cooling means may take any convenient form and in the present disclosure the refrigerant evaporator 16 is located in tank or compartment 18 and is so constructed that the refrigerant evaporating portion 16 cools the holdover 17 while the clothes dryer is inactive. Means are provided for dehumidifying the room air circulated through the passageway 12, while the clothes dryer is inactive. This may be accomplished by locating the refrigerant evaporator 15, the refrigerant condenser 13, and the refrigerant motor-compressor 14 in the passageway 12, together with an air circulating fan 19 driven by the motor 20, which causes room air to enter the passageway 12 at some such point as air inlet 21, be dehumidified in the passageway, and be discharged through air outlet 22 back into the room.

The clothes dryer conveniently may include a rotatable perforated agitator drum 24 located in a stationary casing 25 which may have an insulated covering therearound. The drum 24 may be driven by a clothes dryer motor 26 through the medium of a speed reduction transmission, such as a belt drive diagrammatically indicated at 27. A heater 28 is provided, preferably electric, and may include reflectors 29. If desired, an air inlet 30 may be provided, in casing 25, for the chamber 10 and may be controlled by a damper 31 which is operated by a solenoid 32 to be open while clothes are being dried and to be closed at other times.

The vapor condenser 11 may include a plurality of tubes into which the water vapor from the clothes drying drum 24 may flow and may

be condensed. The water thus condensed flows down the tubes and through the screen 34, which forms the bottom of a removable receptacle 35, and then falls into the bottom of sump 36. Any lint released by the clothes falls into the vapor condenser 11, and then into the screen 34. The water in sump 36 flows through the pipe 37 to a pump 38, driven by motor 20 through transmission 39, from whence the water can be discharged into a drain or stationary laundry tub by the pipe 40.

The holdover medium 17 may store refrigerating capacity by being cooled throughout in the liquid stage, or preferably by a partial or complete change of phase from the liquid to the solid state. Preferably a holdover medium is chosen which has a solidifying temperature slightly above the normal operating temperature of the refrigerant evaporating portion. For example, if the normal temperature of the refrigerant evaporating portion is 40° F., then the holdover may have a freezing temperature slightly above 40° F.

The vapor leaving or being driven from the clothes by the heaters 28 may be driven by its own pressure into the vapor condenser 11; but preferably this vapor is carried by a relatively small volume of air circulating from the room into the opening 30, through the drum 24 and eventually mixing with the room air entering at the opening 21 and thence being discharged through the opening 22, as indicated by the arrows, at a relative humidity that is not harmful to the room in which the apparatus is located.

Controls are provided whereby the apparatus may be operated with the room air dehumidifier operating under automatic controls, or operating independently of any automatic controls. For this purpose, a controller or master switch 50 is provided in the source of electricity, line L₁, which is movable from an off position to either a non-automatic position or to an automatic position. For this purpose, the movable contact arm 51 may be moved from the off position into engagement with the stationary contacts 52, 53, and 54. When arm 51 is brought into contact with the contacts 52 and 53, the dehumidifier operates independently of any automatic controls; and when the movable contact arm 51 engages contacts 53 and 54, the dehumidifier operates under automatic control. In either case the clothes dryer may be energized by manipulation of its individual time controlled switch 64.

The apparatus may operate as a room air dehumidifier alone, without any clothes drying action, and with the master switch 50 in either operating position, as long as dryer switch 64 is in its off position. Under these conditions, the motor-compressor 14 and the fan motor 20 are energized. Compressed refrigerant flows from the motor-compressor 14 to the refrigerant condenser 13 then through the refrigerant restrictor or expander 55, then through the refrigerant evaporating portions 16 and 15 and from thence back to the refrigerant motor-compressor 14. At the same time, room air is circulated by the fan 19, the air entering from the room through the opening 21, in a wall of cabinet 9, into the passageway 12 and thence out through the screened outlet 22. The vapor in the room air is condensed on surfaces of the refrigerant evaporator 15, the condensed water dripping on the floor of the passageway 12, and flowing into the sump 36, from whence it is dis-

charged into a drain or a stationary laundry tub through the pipes 37 and 40 by means of the pump 38. After the air has been dried and cooled by passing over the refrigerant evaporator 15, the air passes over the refrigerant condenser 13 where the air is heated in cooling and condensing compressed refrigerant vapor in condenser 13. The air is then discharged into the room through outlet 22 in a dehumidified condition. During this time, the holdover 17 is cooled to the proper condition by the refrigerant evaporator 16.

The apparatus operates with the dehumidifier under automatic controls when the movable contact arm 51 engages the contacts 53 and 54. The refrigerating system is energized through the line 60, passing either through the thermostatic switch 61 (the bulb 62 of which is embedded in the holdover medium 17) or through the room humidistatic switch 61a, or both. The switches 61 and 61a have off and on adjusted positions, as is well known. As long as the holdover 17 has not been cooled sufficiently, the switch 61 remains closed, and the motor-compressor 14 is energized. As long as the room has not been sufficiently dehumidified, the switch 61a remains closed and energizes the motor-compressor 14. When both the holdover 17 and the room are in proper condition, the motor-compressor 14 is stopped.

The clothes dryer may be energized while the switch 50 is in either active position, i. e., with 51 in contact with either 52 or 54. The electric line 63 from contact 53 passes through the clothes dryer time controlled switch 64, then to the dryer motor 26, solenoid 32 and heater 28 (the other side of the heater may be connected to the neutral line, or if desired to a 220 volt line L₂, as indicated in dotted lines). The dryer switch 64 is of the usual type, having a handle 65 which may be moved from an off position to any one of several "minute" on positions. This movement of handle 65 closes the switch 64 which remains closed until the handle is driven back to the off position by an electric motor or the like, within the switch. In the off position, the switch is opened and its driving motor is deenergized. Switches of this character are well known and hence are not further disclosed herein.

When the master switch or controller 50 is moved to the non-automatic position, i. e. with arm 51 engaging contact 52, the motor-compressor 14 operates continuously. The first refrigerating action is concentrated on the holdover medium 17, and this holdover is cooled to the necessary condition. Thereafter the refrigerant liquid overflows evaporator portion 16 into the evaporator 15, which then proceeds to dehumidify the air entering through opening 21. From that time on, the motor-compressor 14 and fan 19 continue to dehumidify the room air until such time as the switch 50 is moved to some other position.

The damper 31 of opening 30 remains closed by gravity at all times that no clothes drying action is required, since the solenoid 32 is not energized. The damper 31 opens whenever a clothes drying action is required, since the closing of the switch 64 for this purpose automatically energizes the solenoid 32 which in turn causes the damper 31, by way of an arm, bell-crank lever or the like, to open. This damper action prevents the holdover 17 from being unnecessarily warmed when there is no clothes drying action required.

The open position of damper 34 is indicated in Fig. 1 by the dot-dash line showing thereof.

From the foregoing it should be apparent that a novel combined clothes dryer and room air dehumidifier is provided. The provision of a holdover medium for the clothes dryer vapor condenser permits cooling this medium with a relatively small capacity and inexpensive refrigerating system whereby a cooler of great capacity is afforded so as to be effective throughout a clothes drying action of the dryer and so as to maintain the clothes dryer in readiness for a drying action. The combined apparatus will during and after a clothes drying action thereof remove moisture from the air in the room in which the apparatus is located. Thus objectionable high relative humidities in basement or utility rooms is reduced, and rusting or molding of other equipment in such rooms is avoided.

While the embodiments of the invention as herein disclosed constitute preferred forms, it is to be understood that other forms might be adopted as may come within the scope of the claims which follow.

What is claimed is as follows:

1. A combined clothes dryer and room air dehumidifier comprising: a clothes dryer having a damp clothes drying chamber and a vapor condenser; a room air dehumidifier having means forming a passageway through which room air is circulated; a refrigerating system including a refrigerant condensing portion and a refrigerant evaporating portion; a holdover medium thermally associated with said vapor condenser, means for cooling said holdover medium by said refrigerant evaporating portion while said clothes dryer is inactive for drying damp fabrics, and means for dehumidifying the room air circulated through said passageway including said refrigerant evaporating portion and said refrigerant condensing portion.

2. A combined clothes dryer and room air dehumidifier comprising: a clothes dryer having a damp clothes drying chamber and a vapor condenser; a room air dehumidifier having means forming a passageway through which room air is circulated; a refrigerating system including a refrigerant condensing portion and a refrigerant evaporating portion; a holdover medium thermally associated with said vapor condenser, means for cooling said holdover medium by said refrigerant evaporating portion while said clothes dryer is inactive for drying damp fabrics, means for dehumidifying the room air circulated through said passageway including said refrigerant evaporating portion and said refrigerant condensing portion, and said last named means being operable while said clothes dryer is inactive for drying damp clothes.

3. A combined clothes dryer and room air dehumidifier comprising: a clothes dryer having a damp clothes drying chamber and a vapor condenser; a room air dehumidifier having means forming a passageway through which room air is circulated; a refrigerating system including a refrigerant condensing portion and a refrigerant evaporating portion; a holdover medium thermally associated with said vapor condenser, means for cooling said holdover medium by said refrigerant evaporating portion while said clothes dryer is inactive for drying damp fabrics, means for dehumidifying the room air circulated through said passageway including said refrigerant evaporating portion and said refrigerant condensing portion, and means for controlling

the operation of said room air dehumidifying means in response to the temperature of said holdover medium.

4. A combined clothes dryer and room air dehumidifier comprising: a clothes dryer having a damp clothes drying chamber and a vapor condenser; a room air dehumidifier having means forming a passageway through which room air is circulated; a refrigerating system including a refrigerant evaporating portion and a refrigerant condensing portion with a motor-compressor, a holdover medium thermally associated with said vapor condenser, means for cooling said holdover medium by said refrigerant evaporating portion of said refrigerating system, means for dehumidifying the room air circulated through said passageway including said refrigerant evaporating portion and said refrigerant condensing portion, said clothes dryer including a time controlled switch, a controller for connecting said switch to a source of electricity and for simultaneously energizing said motor-compressor of said refrigerating system, and said time controlled switch being operable at will to energize said clothes dryer.

5. A combined clothes dryer and room air dehumidifier comprising: a clothes dryer having a damp clothes drying chamber and a vapor condenser; a room air dehumidifier having means forming a passageway through which room air is circulated; a refrigerating system including a refrigerant evaporating portion and a refrigerant condensing portion with a motor-compressor, a holdover medium thermally associated with said vapor condenser, means for cooling said holdover medium by said refrigerant evaporating portion of said refrigerating system, means for dehumidifying the room air circulated through said passageway including said refrigerant evaporating portion and said refrigerant condensing portion, said clothes dryer including a time controlled switch, a controller for connecting said switch to a source of electricity and for simultaneously energizing said motor-compressor, said time controlled switch being operable at will to energize said clothes dryer, and said controller being movable from its position causing continuous operation of said motor-compressor into another position, while said time controlled switch is connected to said source of electricity, to place the energization of said motor-compressor under the control of a thermostatic switch actuated in response to the temperature of said holdover medium and/or under the control of a humidistatic switch actuated in response to the moisture content of air in the room in which the combined apparatus is located.

6. In combination; a clothes dryer cabinet, a container within said cabinet for receiving damp clothes to be dried, means for heating the damp clothes received in said container, a vapor condenser within said cabinet through which heated moist air leaving the clothes flows, a holdover medium in thermal exchange relationship with said vapor condenser, means for cooling said holdover medium to cause said vapor condenser to remove moisture from the heated moist air flowing therethrough prior to its egress from said cabinet, said cooling means including a refrigerant evaporating portion of a closed refrigerating system within said cabinet, said refrigerating system including another refrigerant evaporating portion isolated from the holdover medium cooling portion thereof, a refrigerant condensing por-

tion and an air circulating means, said air circulating means being adapted to draw air into said cabinet over said another refrigerant evaporating portion and said refrigerant condensing portion of the refrigerating system and to discharge the air from said cabinet, and said another refrigerant evaporating portion and said refrigerant condensing portion of said system condensing moisture out of the air in the room in which the cabinet is located.

7. In combination; a clothes dryer cabinet, a container within said cabinet for receiving damp clothes to be dried, means for heating the damp clothes received in said container, a vapor condenser within said cabinet through which heated moist air leaving the clothes flows, a holdover medium in thermal exchange relationship with said vapor condenser, means for cooling said holdover medium to cause said vapor condenser to remove moisture from the heated moist air flowing therethrough prior to its egress from said cabinet, said cooling means including a refrigerant evaporating portion of a closed refrigerating system within said cabinet, said refrigerating system including another refrigerant evaporating portion isolated from the holdover medium cooling portion thereof, a refrigerant condensing portion and an air circulating means, said circulating means being adapted to draw air into said cabinet over said another refrigerant evaporating portion and said refrigerant condensing portion of the refrigerating system and to discharge the air from said cabinet, said another refrigerant evaporating portion and said refrigerant condensing portion of said system condensing moisture out of the air in the room in which said cabinet is located, and means for rendering said refrigerating system operative in response to the temperature of said holdover medium to maintain said vapor condenser in readiness to remove moisture from heated moist air flowing therethrough.

8. In combination; a clothes dryer cabinet, a container within said cabinet for receiving damp clothes to be dried, means for heating the damp clothes received in said container, a vapor condenser within said cabinet through which heated moist air leaving the clothes flows, a holdover medium in thermal exchange relationship with said vapor condenser, means for cooling said holdover medium to cause said vapor condenser to remove moisture from the heated moist air flowing therethrough prior to its egress from said cabinet, said cooling means including a refrigerating evaporating portion of a closed refrigerating system within said cabinet, said refrigerating system including another refrigerant evaporating portion isolated from the holdover medium cooling portion thereof and a refrigerant condensing portion with a motor-compressor, an air circulating means, said air circulating means being adapted to draw air into said cabinet over said refrigerant condensing portion of the refrigerating system and to discharge the air from said cabinet, said refrigerant condensing portion of said system condensing moisture out of the air in the room in which said cabinet is located, a time controlled switch for energizing and deenergizing said heating means, a

controller for connecting said switch to a source of electricity and for simultaneously energizing and causing continuous operation of said motor-compressor and said air circulating means, and said time controlled switch being operable at will to energize said heating means.

9. In combination; a clothes dryer cabinet, a container within said cabinet for receiving damp clothes to be dried, means for heating the damp clothes received in said container, a vapor condenser within said cabinet through which heated moist air leaving the clothes flows, a holdover medium in thermal exchange relationship with said vapor condenser, means for cooling said holdover medium to cause said vapor condenser to remove moisture from the heated moist air flowing therethrough prior to its egress from said cabinet, said cooling means including a refrigerant evaporating portion of a closed refrigerating system within said cabinet, said refrigerating system including another refrigerant evaporating portion isolated from the holdover medium cooling portion thereof and a refrigerant condensing portion with a motor-compressor, an air circulating means, said air circulating means being adapted to draw air into said cabinet over said refrigerant condensing portion of the refrigerating system and to discharge the air from said cabinet, said refrigerant condensing portion of said system condensing moisture out of the air in the room in which said cabinet is located, a time controlled switch for energizing and deenergizing said heating means, a controller for connecting said switch to a source of electricity and for simultaneously energizing and causing continuous operation of said motor-compressor and said air circulating means, said time controlled switch being operable at will to energize said heating means, and said controller being movable from its position causing continuous energization and operation of said motor-compressor and said air circulating means into another position, while said time controlled switch is connected to said source of electricity, to place the energization of said motor-compressor and said air circulating means under the control of a thermostatic switch actuated in response to the temperature of said holdover medium and/or under the control of a humidistatic switch actuated in response to the moisture content of air in the room in which the cabinet is located.
